UNITED STATES PATENT OFFICE.

EUGENE F. MUELLER AND CLARENCE W. KANOLT, OF WASHINGTON, DISTRICT OF COLUMBIA.

CONTAINER FOR LIQUEFIED GASES.

Application filed July 9, 1921. Serial No. 483,622.

To all whom it may concern:

Be it known that we, EUGENE F. MUELLER and CLARENCE W. KANOLT, citizens of the United States, residing at Washington, District of Columbia, have invented certain new and useful Improvements in Containers for Liquefied Gases, of which the following is a specification.

The invention relates in general to portable dispensing containers for liquefied gases, and specifically to a container suitable for use on an aircraft for storing liquid oxygen and supplying gaseous oxygen for respiration at high altitudes.

15 In the aeronautical art, there is need for a liquid oxygen container which will supply oxygen in its gaseous state to the breathing apparatus without fail at all times when needed. It is, therefore, our purpose to provide a container which will be absolutely safe in this respect.

In accomplishing this object, it is proposed to make a container which will volatilize and deliver oxygen at the rate required for respiration continuously from the moment that liquid oxygen is poured into the container. Such a container will function independently of human control and is thus adapted to meet emergencies automatically.

30 Furthermore, there will be no control apparatus to get out of order and fail at a critical time.

Continuous delivery, of course, represents a loss of gas during flight at the lower altitudes, or at other times when oxygen is not needed for respiration, but this disadvantage is of minor importance when the safety factor is considered.

It is an object also to provide means for preventing delivery of liquid through the gas outlet under unusual conditions, such as inversion of the container. This is important because any liquid oxygen reaching the aviator might cause serious injury.

45 A further object is to provide heat insulation for the container which will permit volatilization to the desired extent, which will withstand hard usage, and whose efficiency will continue throughout long use.

50 Another object is to make the container fire-proof and free from danger of explosion. To this end, materials which could unite with the liquefied gas to form combustible mixtures or compounds have been avoided in the selection of materials for the

construction of the container. Furthermore, a safety valve is provided which will open under excessive pressure from within so as to give vent to the atmosphere in an emergency before a violent explosion can occur.

A still further object is to provide means for indicating the quantity of liquefied gas remaining in the container at any time.

Other objects of the invention will appear as the following specific description is read in connection with the accompanying drawing, which represents the container in vertical cross-section, as designed for use in supplying oxygen for respiration in aviation.

In the drawing, a portable container designed for use on board an aircraft to store and supply gaseous oxygen for respiration at high altitudes is represented by way of illustration. It is to be understood, however, that we do not restrict the application of the inventive idea to this particular use. A container of the nature which will be described in detail hereinafter should prove to be useful in other arts and in other capacities in the aeronautical art. For instance, a container possessing the characteristics which have been outlined briefly in the statement of the objects of the present invention should be useful for supplying gaseous oxygen or hydrogen to internal combustion engines, especially in the case of engines employed in the propulsion of aircraft. The proposed container will be much lighter in weight and more compact than any tank for storing an equivalent volume of oxygen or hydrogen in the gaseous state. Other uses might be as the storage container of oxygen apparatus for medical purposes, as means for storing liquefied hydrogen, or other buoyant gases, on board an airship for inflation of the envelope, etc.

Before describing the suggested form which the invention may take, it may be pointed out also that various changes in the details of construction, substitution of materials, and other obvious modifications may be made in practice without departing from the scope of the invention as defined in the appended claims.

Referring to the drawing by the use of reference characters, numeral 1 designates the container proper which may take the form shown. This chosen form lends symmetry and strength to the device. In this

instance, the side wall is cylindrical and the top and bottom walls are conical in shape. Other points of utility possessed by this particular shape will become apparent as the description progresses.

It has been stated that the principal object of the invention is to provide a container which will volatilize the oxygen, or other element, at the rate desired for delivery through the outlet. It has been discovered that this may be accomplished by insulating the container against outside heat to such an extent that just sufficient heat to produce volatilization at the desired rate can enter. One way of doing this is to provide a double walled container and to interpose between the inner and outer wall members 2 and 3, respectively, an insulating medium possessing such heat conducting properties that only the desired amount of heat can penetrate the composite wall in a unit length of time. In order to give strength to the container walls, the inner and outer wall members 2 and 3 may be made of sheet metal. Copper is a metal suitable for this purpose because it can be soldered with the production of tight joints, it does not corrode readily, and, unlike some iron, does not become brittle at the temperature of liquid oxygen. Of course, some other metal, or even non-metallic material, might prove to be more suitable in practice and may be adopted within the spirit of the invention.

It is intended to fill the space between the wall members 2 and 3 temporarily with insulating material. In seeking a suitable material for this purpose, "calorox" has been chosen. The advantages of calorox are low heat conductivity, low density, and the fact that it is not combustible. The use of combustible material, such as ground cork, in apparatus containing oxygen would be dangerous, for, if such material becomes saturated with liquid oxygen by accident, the product may be a powerful explosive. Considering the properties of the selected insulating material, the space between the wall members 2 and 3, and hence the thickness of the insulating medium, should be such a carefully calculated distance that the small quantity of heat reaching the liquefied gas through the container walls, together with any small quantities of heat which may enter through the filling portion or other conducting paths, will be just sufficient to cause the liquid to evaporate at such a rate that gas will be evolved and delivered at approximately the rate most desirable for the intended use. In this connection, the total area of the container walls, as determined by the size and form of the container, bears a definite relation to the thickness of the insulating medium and must be considered in calculating that thickness.

The use of the inner and outer wall members 2 and 3 is necessitated by the nature of the particular insulating medium which has been adopted. These wall members give form and strength to the container, confine the insulating material, and prevent the penetration of moisture from the atmosphere into the insulating material. Otherwise, such moisture would condense within this material and seriously impair its insulating properties.

In order that the insulating material may be replaced by fresh material when desired, a filling opening 5 may be provided in the outer wall member 3. A suitable location for this opening is at the apex of the bottom wall of the container. A threaded collar 6 may be provided at this opening for engagement with a screw cap 7 which will serve as a convenient closure for the opening.

A strong, secure base for the container may be formed by providing an extension 8 on the cylindrical portion of the outer wall member 3. This extension should project downward to a point lower than the closure cap 7, and should be beaded as at 9 to give increased strength to the base thus formed. When the container has been transported to the desired location for use, it may rest upon this base without danger of becoming overturned except when the aircraft, or other support, becomes seriously tipped or inverted in position. Such a contingency may be provided for by securing the container to the support in any desired manner. It is not considered necessary to show any such securing means in the accompanying drawing, since that would not add to the disclosure of those features of the device upon which novelty is predicated.

In order that liquefied gas may be poured into the container, a filling opening 10 may be provided in the top wall. A convenient location for this opening is at the apex of this wall, and it should extend through the inner and outer wall members and the layer of insulating material. The opening may be lined by a tubular member 11, which is preferably made of a metal of low thermal conductivity. This member 11 should be connected by airtight joints to the inner and outer wall members 2 and 3 of the casing. In this way, the insulating material will be sealed effectively at this point against entrance of moisture from the atmosphere. A convenient way to close the filling opening 10 is to mount a threaded collar 12 on the top wall of the container so as to surround the opening, and to engage a screw cap 13 with this collar. By extending the tubular lining member 11 upwardly past the outer wall member 3 and by fitting this extension snugly within the collar 12, and, by projecting the lower end of the lining member into the casing past the inner wall member 2 and

reinforcing this projecting end of the lining member by a ring 14 interposed between the same and the wall member 3, a rigid mechanical connection will be afforded between the 5 inner and outer wall members 2 and 3. Otherwise, the position of the inner wall member would be unstable.

A safety valve for preventing the occurrence of a disruptive explosion may be provided by constructing the closure cap 13 in the manner shown in the drawing. For this purpose, apertures 15 have been provided in the circular wall of the cap, and a secondary threaded flange 16 is formed inside the cap 10 so as to project into the sleeve 12 which surrounds the filling opening of the casing. A secondary, clamping cap 17 is threaded onto the flange 16 and is adapted to clamp the marginal edge of a sealing member 18, in 15 the form of a thin sheet of frangible material, between cap 17 and flange 16. Apertures 19 are provided in the secondary cap for cooperation with the apertures 15 in cap 13. The sealing member 18 will prevent the 20 escape of fluid under normal conditions. However, should the pressure within the container rise to such a degree that the sealing member becomes ruptured, a vent to the atmosphere will be afforded through the 25 openings 15 and 19. The pressure at which the seal will become broken may be regulated by applying a sealing member of predetermined thickness.

The gas outlet for the container will now 30 be described. This outlet is considered to be one of the novel features since it includes means for preventing the delivery of liquid with the gas, even under the most extreme conditions of practical use. In the construction 35 of this outlet, a tube 20 extends from the geometrical center of the container to one of its walls. In the present instance it has been extended to the top wall at a point adjacent to the filling opening. At this 40 point, the tube enters the space between the wall members 2 and 3 and is preferably soldered to the inner wall member where it penetrates the same, in order to effect a fluid-tight joint. The tube extends through the 45 insulating material to a point preferably located at the bottom of the container, at which point it opens into the space formed within the base flange 8 beneath the container. This space is suitable for the location 50 of a liquid trap, so it is proposed to form such a trap by connecting flange 8 near its base edge with the apex of the container bottom by means of an imperforate wall 21. The annular trap thus formed is designated 55 by the numeral 22. By constructing the wall 21 of thin sheet metal, such as copper, heat will be conducted through the same and flange 8 to the interior of the trap very readily and should cause instantaneous evaporation 60 of any liquid entering the trap

through tube 20. The trap is provided as an additional safeguard which is adapted to function under extreme conditions of practice, or displacement of the inner end portion of tube 20, such as might result in 70 the discharge of small quantities of liquid. The most probable cause of liquid discharge would be the production of spray near the mouth of the delivery tube resulting from violent agitation of the liquid contents of 75 the container. A continuation of the delivery tube is designated by the numeral 23 and shown extending from the trap through the outer wall member 3 of the container into the insulating medium and through the 80 latter to an outlet 24. This outlet may be in the form of a hose connection, as shown, in order that connection may be made between the same and the respirator of the 85 aviator's personal equipment. The inner end of tube 23 should communicate with the trap at such a point that it will not be covered by liquid within the trap except in an extreme case when the latter is full of liquid, or nearly so. Such an occurrence is 90 only remotely possible and need not be given serious consideration.

Aside from acting as an expansion chamber and trap, the space 22 serves an additional purpose. It is adapted to raise the 95 temperature of the gas during its delivery to the respirator. This has a decided advantage, in that warm gas is more comfortable for respiration than very cold gas.

In using the container with the mouth of the delivery tube disposed at its center, the container can be only half full of liquefied gas at any time, without permitting the discharge of liquid through the gas outlet. This necessitates the construction of the container of such a size that sufficient gas for a flight of maximum duration will be delivered when it is only half full. The normal operation of the container is thus provided for, but, in order to permit more nearly complete filling of the container under any unusual conditions which make that desirable, the tube 20 may have an additional mouth at the apex of the top wall of the container. This mouth may be provided by extending a short tube 25 from the tubular lining member 11 to a point of connection with the tube 20, which point is indicated by the numeral 26. It will seldom be necessary to use this additional mouth, so a simple cutoff valve 27 may be connected with tube 25. When this valve is closed, discharge will occur through the mouth of tube 20 alone, whereas, when the valve is open, discharge may occur through either or both mouths. In either event, the presence of the valve will not prevent continuous delivery of gas at all times. It is better to use the container with only half 100 its maximum liquid contents and to have 105 110 115 120 125 130

the valve 27 closed, but it may be used more nearly completely full without much danger of delivering liquid through the outlet. Liquid will only enter the trap in case of 5 splashing or extreme tipping of the container, either of which conditions is not apt to occur in successful altitude flights. The trap will take care of quite a large amount of liquid, so delivery of liquid through the 10 outlet is still guarded against to a considerable degree.

In order to prevent liquefied gas from entering tube 25 when the container is being filled through its filling opening, a tubular 15 shield 28 may be mounted within the lining member 11. This shield should be connected with the lining member above the mouth of tube 25 and should extend downward past the mouth to a point near the 20 lower end of the lining member. This shield should be smaller in diameter than the lining member from its point of attachment to the latter to its lower end, so as to furnish a conduit for gas from the 25 container to the mouth of tube 25.

In order that injury to the container walls may not be caused by differences in pressure between the outside atmosphere and the space containing the insulating material, 30 it is proposed to provide a vent between the said space and the exterior of the container. Since a direct vent through the outer wall member would permit moisture to enter, it has been found more satisfactory to establish 35 communication between the delivery tube and the space between wall members. This may be afforded by the tube 29, which opens into the space just mentioned, and has interrupted sections of the tube 20 connected therewith. When projection of the 40 tube 29 through the outer wall member appears to be a desirable mechanical expedient, its outer end may be closed by means of a screw cap, such as that indicated at 30. A screen 31 of wire gauze, or other suitable 45 pervious material, may be positioned at the inner end of tube 29 to prevent displacement of insulating material. Some other means for connecting the delivery tube with 50 the space between wall members might be used instead of the tube 29. The latter has been chosen simply for the purpose of illustration of one way of accomplishing the desired result. Tube 20 and the conducting 55 passages of the respirator, or other apparatus connected to the container outlet, will therefore act as a vent. Due to the length of the vent path and to the fact that this path extends through a volume of very dry 60 gas, no moisture can enter the insulating material through the vent.

The presence of moisture in the insulating material is not desired because it impairs its efficiency. When this material is first 65 poured into the space between wall mem-

bers 2 and 3, it may contain some moisture, but the latter will be absorbed by the dry gas passing through the tube 29 in contact with the insulating material and will be carried off in the form of vapor. 70

It will be noted that those portions of the delivery tube which are interposed between the inner and outer wall members of the container extend along the inner surface of the outer wall member throughout almost 75 their entire length. The reason for this arrangement is to permit warming of the delivered gas before and after it passes through the trap. The sheets of metal which will thereby be interposed between the gas 80 that is being conveyed and the atmosphere will serve as means for conducting heat to the gas very rapidly.

It may be desirable to determine the amount of liquefied gas remaining within 85 the container from time to time. In order to meet this need, a gage which will give a visual indication of the liquid volume, has been provided. This gage is designated by the numeral 32 in the drawing. It may be located conveniently on the side wall of the container, as shown. The gage which has been selected is a well-known type which is responsive to differences in pressure on opposite sides of its diaphragm 32a. No novelty is considered to reside in this particular gage, nor in its application to the container. In the present instance, one side of the diaphragm is connected by means of a tube 33 with the interior of the container at a point 90 situated as high as possible. By extending tube 33 through the insulating medium to the lining member 11 of the filling opening just below the point of connection between member 11 and the shield 28, this may be 105 accomplished. Another tube 34 has been extended from the other side of the gage diaphragm to the bottom of the container. A suitable construction and disposition of this tube is shown in the drawing, wherein the tube extends through the insulating medium 110 for quite a distance and then penetrates the interior of the container through the inner wall member 2. As the tube approaches the vertical axis of the container it is bent downward toward the apex of the bottom wall, to which latter it may be secured by soldering, or otherwise, to strengthen the tube. An opening 35 is provided in tube 34 near 115 its point of connection with the container wall so as to establish communication between the interior of the tube and the container. Owing to the conical form of the container bottom, the opening 35 will be 120 covered by liquid until the container is practically empty. The other tube 33 being in communication with the gas-filled top portion of the container, the ratio between the fluid pressures acting upon the diaphragm of the gage will be such as to render 125 130

the gage sensitive to changes in volume of the liquid. By graduating the indicator dial of the gage in terms of appropriate units of fluid measure, the gage will indicate changes in volume from the time the liquid contents are poured into the container up to the time that these contents are exhausted sufficiently to uncover the opening 35. It has been demonstrated that, when liquefied gas is stored within the container, none of this liquid will penetrate the tube 34 through opening 35 to an extent sufficient to introduce a material error in the indications of the gage.

A handle 36 may be attached to the container for use in lifting or transporting the same, but it is to be understood that this handle may be omitted, or any other convenient means for moving the container may be provided in practice.

It may be pointed out again, by way of emphasis, that many of the structural details described and illustrated are susceptible of alteration and even replacement by better construction which may be developed in the future. The novel features of the device which are expressed by the suggested structure form the subject-matter of the following claims.

We claim:

1. A dispensing container for liquefied gas including means for causing continuous volatilization of gas at a predetermined rate, and a delivery tube having an opening disposed approximately at the center of the container.

2. A dispensing container for liquefied gas including means for causing continuous volatilization of gas at a predetermined rate, and a delivery tube having an opening disposed approximately at the center of the container, and a trap connected with the delivery tube between the said opening and its outlet adapted to prevent delivery of liquid through the outlet.

3. A dispensing container for liquefied gas including means for causing continuous volatilization of gas at a predetermined rate, and a delivery tube having an opening disposed approximately at the center of the container, and an additional delivery tube communicating with the first mentioned delivery tube and having an opening com-

municating with the interior of the container at a point proximate to its defining wall.

4. A dispensing container for liquefied gas including means for causing continuous volatilization of gas at a predetermined rate, and a delivery tube having an opening disposed approximately at the center of the container, and an additional delivery tube communicating with the first mentioned tube and having an opening disposed proximate to the defining wall of the container, and means for closing the additional tube.

5. A dispensing container for liquefied gas including means for causing continuous volatilization of gas at a predetermined rate, and a delivery tube having an outlet and an opening disposed approximately at the center of the container, and an additional delivery tube communicating with the first mentioned tube and having an opening communicating with the interior of the container at a point proximate to the defining wall of the latter, and a liquid trap connected with the first mentioned delivery tube between its point of communication with the additional tube and the outlet.

6. A dispensing container for liquefied gas having means for causing continuous volatilization of gas at a predetermined rate embodying heat insulated walls including straight side walls and a tapering bottom, an extension of the side walls projecting downward past the apex of the bottom to form a supporting base for the container, a liquid trap formed within the space between the said wall extension and the container bottom, and a gas delivery conduit leading from the interior of the container through the trap to an outlet.

7. In a dispensing container for liquefied gas including heat insulating walls, a gas delivery conduit leading from the interior of the container to an outlet, a liquid trap disposed outside the container walls and below said container and in communication with the said conduit, said trap having walls of material possessing high thermo conductivity.

In testimony whereof we have affixed our signatures.

EUGENE F. MUELLER.
CLARENCE W. KANOLT.
